UNITED STATES PATENT OFFICE.

MAURITZ C. INDAHL, OF PHILADELPHIA, PENNSYLVANIA, ASSIGNOR TO LANSTON MONOTYPE MACHINE COMPANY, OF PHILADELPHIA, PENNSYLVANIA, A CORPORATION OF VIRGINIA.

STRIP-PERFORATOR.

1,378,414.

Specification of Letters Patent.

Patented May 17, 1921.

Application filed September 20, 1919. Serial No. 325,165.

To all whom it may concern:

Be it known that I, MAURITZ C. INDAHL, a citizen of the United States, residing at Philadelphia, county of Philadelphia, and 5 State of Pennsylvania, have invented certain new and useful Improvements in Strip-Perforators; and I do hereby declare the following to be a full, clear, and exact description of the same, reference being had 10 to the accompanying drawings, forming a part of this specification, and to the characters of reference marked thereon.

This invention relates to perforating machines particularly machines for producing 15 one or more longitudinal series of equally spaced feed perforations in a strip of paper or the like for use in connection with suitable mechanism such as a type-casting machine of the kind well known as manufactured 20 by Lanston Monotype Machine Company; the general organization of a machine of this kind may be found described in United States Patent No. 625998 dated May 30, 1899. The feed perforations in the strip 25 are adapted to engage with teeth on a suitable feed roller in the machine by the operation of which roller the paper is fed step-by-step through the machine. The same marginal feed perforations are used for the feed 30 of the strip through the keyboard machine, represented, for example, by Patent 944,405, dated December 28, 1909, which machine produces key controlled signal perforations in the strip, the signal perforations being 35 located intermediate of the marginal feed perforations and having the function of controlling the operation of the casting machine through which the controller strip is fed. The paper controller strip may be such as 40 is illustrated in Patent 857,974, dated June 25, 1907.

The mechanism of the present invention is, in the embodiment shown, adapted to produce the marginal perforations in a controller strip of this kind; it is similar in 45 some respects to the perforating machine disclosed in Patent 915,537 dated March 16, 1909, and the present invention may be regarded as in the nature of an improvement 50 upon the mechanism shown in said patent.

The main object of the present invention

is to produce a mechanism by which accurate perforations may be made with great rapidity in a strip of suitable material such as paper. Machines in which the strip is 55 moved step-by-step are necessarily slow in action as compared with those in which the paper is advanced continuously. Of the latter kind two types are well known, the rotary and the high speed reciprocating punch 60 types. In the rotary type the punching is done by a series of peripheral punches on a rotary member, which punches coöperate with a corresponding series of dies on a second rotary member between which members 65 the strip is advanced at a uniform speed by the pull of the punches in the perforations. On account of this pull and because of the fact that the punches enter the paper at an angle and withdraw at another 70 angle, the perforations are not accurate and clear cut but are often elongated, rough and fuzzy. The high speed reciprocating punch type of perforator is illustrated in the above mentioned Patent 915,537; the punches enter 75 and leave the paper in a plane perpendicular to the plane of the paper and this arrangement is conducive to the producing of perfect perforations. The paper is at all times advanced at a uniform rate, however, and 80 except when this rate is relatively slow and the punch reciprocating speed is extremely high, the perforations in the paper are imperfect due to the drag of the paper laterally against the punches. The mechanism 85 of the present invention is designed to permit of high paper speed without an accompanying excessive punch reciprocating speed and to prevent drag of paper against punch or any other strain or tear producing 90 causes. These desirable results are brought about by driving the punches along with the paper and at substantially the same speed as the speed of the paper and reciprocating the punches axially to perforate the paper at 95 a time when they are traveling in unison therewith. After the perforating has been completed the punches are moved reversely or in an opposite direction, to an initial position and the operation is repeated for each 100 perforation. Further objects and descriptive details of my invention will appear

hereinafter in connection with the description of the embodiment shown in the accompanying drawings in which—

Figure 1 is a side elevation of the perforating machine.

Fig. 2 is a vertical section enlarged of a portion of such machine.

Fig. 3 is a plan view of the punch mechanism.

Fig. 4 is a section on approximately the line 4—4 of Fig. 3.

Fig. 5 is a section on approximately the line 5—5 of Fig. 3.

Fig. 6 is a section on approximately the line 6—6 of Fig. 3.

Fig. 7 is a front view of the inspector mechanism.

Fig. 8 is a rear elevation thereof.

Fig. 9 is a section along approximately the line 9—9 of Fig. 8.

Fig. 10 is a section approximately on the line 10—10 of Fig. 8.

Fig. 11 is a detailed perspective showing the trip mechanism for stopping the machine, and

Fig. 12 is an enlarged perspective view of the head of a punch actuating lever.

The frame of the machine illustrated consists of the upstanding members 12, the base 30 plate 13 and the braces 14, 14' connecting said upstanding members. Journaled in the members 12 are the perforating device shaft 15, the feeding drum shaft 16, and the winding roll shafts 17, 17'. At one end of the 35 machine the shafts 16, 17 and 17' are provided with gears 18, 19 and 19' respectively, and all of these gears mesh with a driving gear 20, secured to shaft 21. The gear wheel 20 is driven by the worm drive device 22 40 shown in Fig. 1, this device 22 connecting the gear 20 with the shaft 15. On the end of the latter shaft are loose and driving pulleys upon either of which rides a belt 23, (Fig. 2) maintained tight by the idler pulley 24 mounted upon the idler frame 25 provided with an extension upon which is 45 mounted a roller 27 to engage with the end of lever 28 pivoted at 29 and carrying a weight 30 at its outer end. This weight 50 serves, as will be readily understood, to press the idler wheel 24 against the belt 23 and keep it tight. The idler frame 25 is pivoted at 26 to a bracket 31 secured to shaft 32 slidably mounted in the frame 12 where- 55 by movement of the bracket and shaft longitudinally will move the idler pulley and by the latter the belt 23 between its two positions of contact with either the loose or the tight pulley on shaft 15. The devices 60 for moving this bracket and shifting the belt will be described hereinafter.

Projecting forwardly from the frame members 12 is the bracket 33 which supports at its end the shaft 34 upon which the roll 65 of paper 35 to be perforated is wound. This

paper as it unrolls is fed under an idler roller 36, the shaft 37 of which is movable in a slot 38 running lengthwise of the bracket 33 and radially with respect to the roll 35; this idler frictionally engages with the periphery of the roll 35 and guides the strip as it leaves the roll 35; the paper now runs over a roller 39 and then down around a roller 40 the axle of which engages in the slots 41 in the frame 33 and is movable vertically in said slots. The paper travels from said roller 40 to roller 42 journaled in the bracket 33 so that the portion of the paper under roller 40 is in the form of a yielding loop kept tight by the weight of the roller 40. From roller 42 the paper travels across a space in which the punch and die perforating mechanism is located and after passing through said mechanism engages with a toothed feed drum 43 on the shaft 16. After leaving the drum 43 the paper engages successively with the front surface of the automatic inspector plate 44, and the roller 45 on shaft 17, and finally rolls up on a core 46 which is located between the rollers 45, 45', 80 90 on shafts 17, 17' respectively and which as the paper rolls upon it grows in size pushing upward the roller 47.

The driving of the paper is accomplished from shaft 15 through the worm gearing 95 mechanism 22, the gear 20 and the gear 18 on shaft 16, which, as has been before stated, bears upon it the drum 43; the latter is provided with peripheral series of teeth for engagement with the perforations of the 100 paper. The axle 48 of the roller 47 is secured at its ends to the vertically slidable cross piece 49 which is shown in section in Fig. 2 and in dotted lines in Fig. 1. When the roll of paper on the core 46 has grown to the desired size the frame 49 will have risen sufficiently to engage with an adjustable stop in the form of a screw bolt 50 (Fig. 1) and raise it together with the vertical rod 51 to which the bolt 50 is attached. This rod extends along one end of the machine vertically and is constantly pressed downward by its spring 51': it has at its lower end a latch portion which engages behind a projection 52 (Fig. 11) upon a bell crank lever 53, provided with a handle 54, and secured to a vertical shaft 55. This shaft 55 is provided on a level with the belt shifter frame 31 with a horizontal arm 56 (Fig. 1) engaging with the shaft 32. When the latch 51 has been raised, as previously pointed out, it releases the lever 53 and this lever is pressed by the spring 57 to rock the shaft 55 and move the arm 56 to slide the frame 31 and associated belt shifting devices and thus shift the belt from its tight to its loose pulley. It may readily be seen that in this way when the finished paper roll on the core 46 has become sufficiently large the mechanism will automatically op- 120 125 130

erate to stop the further operation of the machine.

The cross member 49 is provided with an angularly projecting frame 58 holding a 5 slidable thin member 59 normally maintained in uppermost position by a spring 60. When the finished roll has become large enough to stop the machine the operator removes this roll and allows the slide 49 to 10 drop to its lowermost position. A new core 46 is placed between the rollers 45, 45' and the end of the paper coming from the perforating device is wrapped around this new core. In order to start the core's rotation 15 20 25 to roll the paper about it as the paper is delivered to it, the thin member 59 may be pushed downwardly manually to squeeze the end of the paper between the core and the periphery of the roller 45. This member 59 may also be used in an obvious manner for tearing the paper when the finished roll is being removed from the machine.

The inspector mechanism located just above the toothed feed drum 43 is provided 25 with a guide rod 61 near its lower end around which the paper is led in feeding and with a smooth surface above such rod over which the paper runs in its movement to the winding roll 45. This surface is provided 30 with a slot 62 extending crosswise of the paper and being equal in length to the width of the paper except for the marginal perforations therein. Leading through the member 44 from the slot 62 is a channel 63 35 which connects with an enlarged chamber 64 in which is a filter screen 65 (Fig. 10). Behind this screen is a channel 66 leading to a valve 67 provided with ports connecting the channel 66 with the pipe 68 connecting 40 ed with a vacuum producing mechanism (not shown). The slot 62 is also connected by a channel 63' with a chamber 64' (Fig. 9) provided with a filter screen 65' and this chamber is connected by a channel 69 with 45 a diaphragm chamber 70 in which a diaphragm 71 horizontally disposed is located, this diaphragm being connected centrally thereof with a valve 72 closed against its seat in the plate 44 when the diaphragm is 50 in its normal or upper position as shown. The valve stem extends upwardly into a bore in the plate 44 and is provided with a lower grooved portion 72' communicating with pipe 73 and with the atmosphere 55 through the port 74; the stem is also provided with an upper grooved portion 72'' between two portions fitting the bore, said upper grooved portion being connected through channels 75 with the constant air 60 inlet pipe 76, the latter leading from suitable air compressing mechanism (not shown). A spring 77 is located in the bore above the valve stem and is held to exert downward pressure against the valve stem 65 by the screw secured plate 77'. The pipe

73 leads, as is shown in Fig. 1 to a motor 78 located in proximity to the latch 51 previously mentioned. When air is permitted to pass through the pipe 73 it operates the motor 78 and raises the arm 79 secured to 70 the latch 51 thus causing the stopping of the machine in the manner hereinbefore set forth.

The diaphragm 71 is normally held in its upper position by the vacuum in the chambers 64, 64', the slot 62, the channels 63, 63', 66 and 69 and the chamber 70, the vacuum being possible because of the sealing contact of the paper with the face of plate 44. When a defect in the form of an air admitting perforation in the paper passes over the slot 62 atmospheric air will rush through said perforation and destroy the vacuum thus causing the diaphragm 71 to drop assisted by the spring 77. As soon as the diaphragm drops even slightly the valve 72 is opened and a copious rush of air through the air port 74 completely destroys the vacuum and prevents the diaphragm from jumping up to its normal position as soon as the defect in the paper has passed and the slot 62 is again sealed. The valve 67 is provided with a head 67' (Fig. 8) which may be turned by a wrench, to connect by its passages the vacuum channel 66 90 and the chamber 64 with the constant air pipe 76 through the channels 80. In this manner air under pressure is caused to flow through the screen 65 in opposite to normal direction to clear it and blow accumulations 95 of paper dust and cuttings through the slot 62. In like manner fragments of paper are removed from the screen chamber 64' by removing the plug 81 in the face of the inspector plate 44 and applying air pressure 100 to the passages 82 leading behind the screen 65'.

The diaphragm 71 is provided with a depending extension 83 which when the diaphragm drops engages the bell crank lever 84 pivoted at 84' to the plate 44 and having a depending spring arm at all times in the path of movement of an extension 85 (Fig. 2) on the belt shifter frame.

When the diaphragm extension 83 drops 115 to its low position due to a defect in the strip the bell crank is rocked by it and the spring arm comes against the projection 85. At the same time air from the passages 75 is admitted through the valve portion 72'' 120 to the pipe 73 and to the trip motor 78 and the belt shifter frame 31 is moved in a manner previously described to shift the belt to the loose pulley to stop the machine. In doing this the projection 85 moves the 125 spring arm of the bell crank 84 to lift the valve 72 to normal position and at the same time cut off air pressure from the motor 78 and allow the latter to exhaust through the pipe 73 and the valve portion 72'. The mo- 130

tor being exhausted the latch 51 is forced down by its spring 51'. In restoring the belt to the tight pulley the operator moves the handle 54 against the spring 57 to normal 5 position as shown in Fig. 11, thus moving the belt shifting mechanism through the medium of the shaft 55 and the arm 56; the latch 51 engages with the projection 52 on the bell crank lever 53 and holds it and the 10 handle in machine operating position. The inspector mechanism thus causes a stopping of the machine, but the machine in stopping sets the inspector mechanism in position to act again and releases the latch 51 so that it 15 will operate as soon as the handle 54 is shifted to start the machine again. When the valve 62 is thus seated the air exhausting devices produce a new vacuum in the dia- 20 phragm chamber 70 and the vacuum system, it being understood that the defect has moved because of the momentum of the ma- 25 chine so as to be out of communication with the slot 62 so that the latter is again sealed. This vacuum will of course maintain the 25 valve 72 in its seated position. The depending arm of the bell crank 84 is preferably made flexible and therefore yielding to avoid the necessity of providing an adjustment for regulating its position when valve 72 is 30 closed to conform with the position of extension 85 when the belt has been shifted to the loose pulley.

A vacuum pipe 86 extends along the front of the machine and is provided with hoods 35 87 leading above the dies of the perforating mechanism: its purpose is to remove by suction the nibs and paper fragments produced by the perforating operation.

The vertically movable roller 40 main- 40 tains a certain tension on the strip as it un- winds from the supply roll 35. This roller is connected by a depending link 88 with the end of a lever 89 bearing a double cam 90 on its pivotal axis. This cam is rocked 45 as the roller 40 moves up and down and produces equal pressure upon two levers 91, 91' pivoted centrally to the frame extension 33 and connected by rods 92, 92' respectively with the brake levers 93, 93', there being 50 yielding connections between the levers 91, 91' and the rods 92, 92' so that the brakes are applied yieldingly. The brake levers are each pivoted at one end to the frame 33, one on one side of the axle 34 for the sup- 55 ply roll 35 and the other on the other side thereof; the rods 92, 92' are connected with the other ends of these levers and the central portions thereof are adopted to contact frictionally with the axle 34 at dia- 60 metrically opposed sides thereof.

When the machine is stopped, as before pointed out, roll 35 will continue to rotate due to its momentum and a slack in the strip will be produced which will cause the 65 roller 40 to drop; this action will move the

cam lever 89, cam 90, the levers 91, 91' and apply the brakes 93, 93' to stop the rotation of the roll. Upon starting the machine the slack will be first taken up and this will cause the roller to rise and with this action, 70 it will be clear, the brake pressure will be reduced or removed from the axle 34 and the roll 35 will be free to unwind.

The perforating mechanism, as has been stated before, is operated from shaft 15 75 journaled in the frame members 12 and being driven by the belt 23. The punch and die mechanism is supported upon a frame 94 secured by bolts 94' to the brace 14' and having a centrally projected portion 95 80 through which an axle 96 extends above and parallel with the shaft 15. The brace 14' is secured to the frame 12 by screws through apertures 14" (Figs. 1 and 3) in the brace 14'. Supported so as to rock upon this 85 axle 96 is the punch supporting frame 97 having depending yoke portions 97' for engagement with the two cams 98 on the shaft 15. Above the axle 96 the frame extends longitudinally thereof and holds the vertical punch guiding sleeves 99 which are centrally bored to accommodate the punches 100. The punches are provided with heads at their lower ends and these heads are slidably inserted into punch operating and 95 holding levers 101, extending horizontally from the punch heads to a supporting member 102 to which they are pivoted at the point 103. The member 102 is secured to the brace 14' by screws 102'. The heads 101' of 100 the levers 101 are inserted through slots 104 in the cams 105 and when so positioned rest in complementary, annular grooves in said cams so that the latter produce both the upward punching motion and the downward withdrawing motion of the heads 101' and their punches 100. This axial reciprocation of the punches may be a quick one because the active portions of the cams take up, as shown, not more than 60° of the circumference. The paper strip is led between the frame 97 and an upper member 106 bolted to the frame 97 by the bolts 107, but separated by packing sufficiently so that the 110 paper has a channel through which it may be advanced. In the member 106 are the dies 108 which are held down by a die holding member 109 centrally bored so that the paper nibs cut by the punch and die may move upwardly through this holder 109 and escape 120 to the vacuum pipes 86, 87. The holder 109 is held in place by the spring member 110, maintained normally in down position by the cam handle 111 pivoted to a post 112 secured to the member 106. Upon rotating the handle 111 upwardly the spring 110 will be relieved of its pressure upon the die holder 109 and the spring may then be moved laterally and the holder removed. The die itself can then readily be picked out 130

by a suitable instrument. The punches may be removed by rotating the machine until the slots 104 are in registry with the heads 101' of the levers 101, then removing the 5 securing screws in the apertures 14" and taking off from the machine the bracket 14', the frame 94 and the associated punch and die mechanism, after which upon removing the screws 102, the levers 101 and their 10 supporting members 102 may be drawn back in an obvious manner to release the punch heads; the latter may now be grasped by the heads and pulled from their guiding sleeves 99.

15 The punch operating cams are keyed to the shaft 15 and the cams for rocking the frame 97 are formed as an integral part of said shaft. The latter cams may be termed eccentrics because of their action in rocking 20 the frame 97 by a crank motion from a position of rest through a maximum speed to the next position of rest. In the operation of the machine therefore the frame rocks forward and backward during each revolution 25 of shaft 15 with a momentary period of rest between motions. The full punching operation is accomplished within a period of 60° or one-sixth of the time of each revolution and while the frame 97 is rocking forwardly. The result is that the full punching 30 operation, which includes the inserting and withdrawing, takes place when the frame 97 is near the maximum speed portion of its forward motion. The punches and 35 dies therefore are driven along with the strip at practically the same speed as the strip and the latter is driven continuously and uniformly by the toothed feeding drum. It is apparent therefore that the punches 40 neither pull nor act as a drag upon the paper but act at all times in a plane substantially perpendicular to the strip; the latter is relieved of all strain and the perforations are accordingly accurate. During the 45 return motion of the frame 97 no axial movement of the punches takes place and thus the perforations in the paper are equally spaced. The machine, as described, is capable of high speed and of consequent 50 great capacity of production, particularly as compared with perforating machines utilizing a step-by-step feed for the strip. The invention is not limited, however, to a machine in which the paper is fed continuously or to the mechanism shown and described but is to be interpreted in the light of the scope and spirit of the appended claims.

I claim:

60 1. In a paper strip perforating machine, the combination with means for feeding the strip continuously at a uniform speed, of a perforating mechanism comprising an oscillatory punch carrier mounted on a fixed axis and having a paper passage there-

through at one side of said axis, punches mounted in said carrier to move radially with respect to said axis to intersect the paper passage, a drive shaft mounted in bearings parallel with and on the opposite 70 side of said axis from the paper passage, cams on said shaft coöperating with the punches to reciprocate the latter, and eccentrics on said shaft coöperating with the punch carrier to oscillate the same during 75 the reciprocation of the punches.

2. In a paper perforating machine, the combination with means for feeding the strip continuously at a uniform speed, of a 80 perforating mechanism comprising an oscillatory punch carrier, mounted on a fixed axis and having a paper passage therethrough parallel with but remote from the axis, punches mounted in said carrier to move radially with respect to the axis to 85 intersect the paper passage, a drive shaft parallel with the axis and on the opposite side of the same with respect to the paper passage eccentrics on said shaft coöperating with the punch carrier for oscillating the 90 same, and cams on said shaft coöperating with the punches for positively effecting movement of the punches in both directions, whereby the punches may be projected to perforate the paper during the time the 95 punch carrier is moving at its highest speed and be withdrawn from the paper before the carrier reaches the end of its movement.

3. In a paper strip perforating machine, the combination with means for feeding the 100 strip continuously at uniform speed, a perforating mechanism comprising an oscillatory punch carrier mounted on a fixed axis and having a paper passage therethrough at one side of said axis and eccentric embracing arms at the opposite side of said axis, an operating shaft parallel with the axis, eccentrics thereon embraced by said operating arms of the carrier whereby the carrier is oscillated, reciprocatory punches 105 mounted in said carrier and intersecting the axis, and cams mounted on said shaft for reciprocating the punches.

4. In a paper strip perforating machine, the combination with means for feeding the 115 strip continuously at a uniform speed, of a perforating mechanism comprising an oscillatory punch carrier mounted on a fixed axis and having a paper passage therethrough at one side of said axis and eccentric embracing arms on the opposite side of said axis, a drive shaft, eccentrics on said drive shaft coöperating with the arms on the carrier for oscillating the latter, radially movable punches mounted on said carrier to intersect the paper passage, punch supporting arms mounted on fixed centers and coöperating with the inner ends of the punches and cams on said shaft coöperating with the punch arms and punches for reciprocating 120 125 130

the latter during the oscillation of the carrier.

5. In a paper strip perforating machine, the combination with means for feeding the strip continuously at a uniform speed, of a perforating mechanism comprising an oscillatory punch carrier mounted on a fixed axis in a detachable head and having a paper passage therethrough at one side of said axis, and operating arms at the opposite side of said axis, an operating shaft, eccentrics on said operating shaft coöperating with the punch carrier arms for operating the latter, punches movable radially in said carrier to intersect the paper passage, punch supporting arms mounted on fixed axes and carried by said detachable head, and cams mounted on said shaft for coöperation with said punches and their arms, whereby the punch carrier, punches and supporting arms

for the punches may be removed as a unit for the renewal or repair of the punches.

6. A perforating machine embodying the following instrumentalities, to-wit: a punch and die mechanism for perforating marginal feed perforations in a controller strip, a feeding drum provided with teeth for engagement with the said perforations, gearing for rotating said drum to draw the strip from a feed roll, a punch and die operating shaft, a cam on said shaft for reciprocating said punch axially to perforate the strip, a second cam on said shaft for reciprocating the punch and die mechanism laterally whereby it moves along with the paper during the perforating thereof and in an opposite direction between perforations, gearing for rotating said shaft and a common driving means for said gearings.

MAURITZ C. INDAHL.
